CLAIM

The ornamental design for a Beverage Can as shown and described.

DESCRIPTION

FIG. 1 is a top perspective view of a Beverage Can according to our design;

FIG. 2 is a top perspective view of the Beverage Can taken 90 degrees from the view of FIG. 1;

FIG. 3 is a top perspective view of the Beverage Can taken 180 degrees from the view of FIG. 1;

FIG. 4 is a top perspective view of the Beverage Can taken 270 degrees from the view of FIG. 1;

FIG. 5 is a front elevation view of the Beverage Can taken from the same angular position as the view of FIG. 1;

FIG. 6 is a front elevation view of the Beverage Can taken 90 degrees from the view of FIG. 5;

FIG. 7 is a front elevation view of the Beverage Can taken 180 degrees from the view of FIG. 5;

FIG. 8 is a front elevation view of the Beverage Can taken 270 degrees from the view of FIG. 5;

FIG. 9 is a bottom elevation view of the Beverage Can taken from the same angular position as the view of FIG. 1;

FIG. 10 is a bottom elevation view of the Beverage Can taken 180 degrees from the view of FIG. 9;

FIG. 11 is a top plan view of the Beverage Can; and

FIG. 12 is a bottom plan view of the Beverage Can.

The broken line portions of the figures are included to show unclaimed subject matter only for the purpose of illustrating environment and form no part of the claimed design.

The region between the dash-dot line is claimed, as the dash-dot line represents the boundary of the claimed design.

1 Claim, 11 Drawing Sheets
